(57) **CLAIM**

I claim, the ornamental design for a license plate frame, as shown and described.

DESCRIPTION

FIG. 1 is a top plan view of a license plate frame, with web(s), and spider(s) on the right, showing my new design;
FIG. 2 is a top perspective view thereof;
FIG. 3 is a front elevational view thereof;
FIG. 4 is a right side elevational view thereof;
FIG. 5 is a bottom view thereof;
FIG. 6 is a bottom perspective view thereof;
FIG. 7 is a top plan view of a license plate frame, with web(s), and spider(s) on the left;
FIG. 8 is a top perspective view thereof;
FIG. 9 is a front elevational view thereof;
FIG. 10 is a right side elevational view thereof;
FIG. 11 is a bottom view thereof;
FIG. 12 is a bottom perspective view thereof;
FIG. 13 is a top plan view of a license plate frame, with web(s), and spider(s) on the left and right;
FIG. 14 is a top perspective view thereof;
FIG. 15 is a front elevational view thereof;
FIG. 16 is a right side elevational view thereof;
FIG. 17 is a bottom view thereof; and,
FIG. 18 is a bottom perspective view thereof.
The broken lines in the drawings illustrate portions of the license plate frame which forms no part of the claimed design.
